MATERIAL FOR HAND BAGS, &c.

No D18,002.

Patented Jan. 3, 1888

UNITED STATES PATENT OFFICE.

HENRY MEHL, OF HOBOKEN, NEW JERSEY.

DESIGN FOR MATERIAL FOR HAND-BAGS, &c.

SPECIFICATION forming part of Design No. 18,002, dated January 3, 1888.

Application filed November 25, 1887. Serial No. 256,179. Term of patent 7 years.

To all whom it may concern:

Be it known that I, HENRY MEHL, of Hoboken, in the county of Hudson and State of New Jersey, have invented a new and original 5 Design for Material for Hand-Bags and other Fancy Goods, of which the following is a specification.

Reference is to be had to the accompanying photograph, forming a part of this specification, and which is a plan view of my design.

The leading feature of my design consists in the representation in relief of various animals and birds in various attitudes, each species of animals and the birds being represented

as separately grouped in a series of panels 15 separated by vines and flowers.

I claim—

The design for material for hand bags and other fancy goods herein shown and described, the same consisting of the representation in 20 relief of various animals and birds in various attitudes, represented as separately grouped in a series of panels separated by vines and flowers.

HENRY MEHL.
